DESIGN FOR A VACUUM RELAY

William W. Eitel and Jack A. McCullough, San Bruno, Calif., assignors to Eitel-McCullough, Inc., San Bruno, Calif., a corporation of California

Application February 11, 1942, Serial No. 105,760

Term of patent 14 years

To all whom it may concern:

Be it known that we, William W. Eitel and Jack A. McCullough, citizens of the United States of America and residents of San Bruno, county of San Mateo, State of California, have invented a new, original, and ornamental Design for a Vacuum Relay, of which the following is a specification, reference being had to the accompanying drawing, forming part thereof.

Referring to the drawing, the figure is a per-

spective view of the vacuum relay, showing our new design.

The opposite side of the vacuum relay is substantially identical with that shown.

We claim:

The ornamental design for a vacuum relay, substantially as shown and described.

WILLIAM W. EITEL.
JACK A. McCULLOUGH.
